United States Patent Office.

ALBERT MOORE AND A. D. HOWES, OF SOUTH ADAMS, MASSACHUSETTS.

Letters Patent No. 77,517, dated May 5, 1868.

IMPROVEMENT IN STEAM GLOBE-VALVES.

The Schedule referred to in these Letters Patent and making part of the same.

TO ALL WHOM IT MAY CONCERN:

Be it known that we, ALBERT MOORE and A. D. HOWES, of South Adams, in the county of Berkshire, and State of Massachusetts, have invented a new and improved Double Steam-Valve; and we do hereby declare that the following is a full, clear, and exact description thereof, which will enable those skilled in the art to make and use the same, reference being had to the accompanying drawings, forming part of this specification.

The object of this invention is to furnish a valve for steam, water, and gas, or other fluids or liquids, constructed in such a manner that it shall be durable and simple and perfect in its operation; and it consists in the arrangement of two valves with a revolving screw-stem, and in the construction and arrangement of parts as hereinafter described.

Figure 1 represents a vertical central section through the line xx of fig. 2.

Figure 2 is a sectional view through the line yy of fig. 1.

Similar letters of reference indicate corresponding parts.

A A' is the shell or body of the valve.

B is the valve-stem.

C C are the valves.

D is the valve-block, in which is formed a female screw for the screw-thread on the stem.

E represents the valve-seats.

The shell is made of two pieces of metal, which are secured together by screws, f , forming a valve-chamber, B'. The valve-seats are in the part A, and the valves with the stem are attached to and supported by the part A'.

The valve-stem is stepped into the part A, as seen at g , and it is prevented from moving up or down (or longitudinally) by the collar h .

J is a stuffing-box, around the upper portion of the shell A' and the stem.

The valves are attached to wings or flanges on the block D, as seen in the drawing, so that, when the stem is revolved, they move simultaneously.

The block D is square in its cross-section, where it plays in A', as seen in fig. 2, the valves being secured to the projecting flanges theron.

The course of the steam or water is indicated by the arrows.

By taking out the screws f and removing the part A', the valves and seats are exposed for inspection or repairs.

There being no grinding or revolving motion given the valves, they are not liable to wear, and the whole arrangement is such that simplicity, durability, and efficiency are combined.

Having thus described our invention, we claim as new, and desire to secure by Letters Patent—

1. The shell, formed of the parts A A', with the valve-chamber B', substantially as described.
2. The block D and the valves C C, in combination with the shell and valve-stem B, when arranged substantially as shown and described.

ALBERT MOORE,
A. D. HOWES.
